FOOT BOARD FOR A BEDSTEAD

William J. Carr, Gardner, Mass., assignor to Heywood-Wakefield Company, Gardner, Mass., a corporation of Massachusetts

Application March 9, 1954, Serial No. 29,427

Term of patent 3½ years

(Cl. D5—4)

Fig. 1

Fig. 2

To all whom it may concern:

Be it known that I, William J. Carr, a citizen of the United States and a resident of Gardner, county of Worcester, and Commonwealth of Massachusetts, have invented a new, original, and ornamental Design for a Foot Board for a Bedstead, of which the following is a specification, reference being had to the accompanying drawing, forming a part thereof, in which Fig. 1 is a front perspective view of a foot board for a bedstead, showing my new design, and Fig. 2 is a fragmentary sectional view on the line 2—2 of Fig. 1, but on a larger scale than that of Fig. 1.

The broken line disclosure depicting a portion of a bedstead is for illustrative purposes only.

I claim:

The ornamental design for a foot board for a bedstead, substantially as shown and described.
